UNITED STATES PATENT OFFICE.

JULIUS BRENZINGER, OF MOUNT VERNON, NEW YORK.

CAN-HEADING MACHINE.

1,230,556.

Specification of Letters Patent. Patented June 19, 1917.

Application filed September 29, 1913. Serial No. 792,295.

To all whom it may concern:

Be it known that I, JULIUS BRENZINGER, a citizen of the United States, residing at Mount Vernon, in the county of Westchester and State of New York, have invented certain new and useful Improvements in Can-Heading Machines, of which the following is a specification.

This invention relates to machines for securing the tops and bottoms to the body portions of sheet metal containers, such as what are known as tin cans, by the double seaming process. The present invention contemplates further improvements, particularly by way of simplification, in connection with a can heading machine such as shown and described by me in my earlier Patent, No. 1,167,346, granted January 4, 1916, and further contemplates additional improvements in means for automatically feeding the assembled can parts to the seaming mechanism, such as shown and described by me in another earlier Patent No. 1,167,345, granted to me on the same date.

It will be apparent that in the provision of mechanism for automatically feeding the assembled can parts successively to the seaming mechanism, there are a number of essentials for which provision must be made. In the first place, the can bodies with the tops or bottoms positioned thereon either by hand or by suitable assembling mechanism, particularly if the containers are to be finally sealed with the contents therein, must be conveyed in such manner to the seaming mechanism as to retain each can body and its top or cover in their properly assembled condition, so that these parts will be relatively positioned for the seaming operation. Furthermore, it will be apparent that while the movement of the containers must be intermittent, in order to provide periods of rest during each of which a seaming operation is performed, such movement must be steady and the actuating mechanism such that the containers will not be abruptly started and stopped or otherwise jarred in transit, so that the loose tops or bottoms may not be dislodged while being advanced to and positioned in the seaming mechanism.

Still furthermore, it will be apparent that the operations of the feeding and seaming mechanism must be necessarily interrelated in order that the seaming operation be performed while the container which has been

positioned is at rest. Still furthermore, when the container to be sealed is brought to proper position, it must be gripped by the seaming mechanism in such manner that the top or bottom will not be dislodged by initial engagement with the seaming mechanism therewith.

In attempting to provide a machine having the qualities and free from the objections suggested above, I have also kept in mind the simplification of the seaming mechanism with particular reference to the actuating means therefor, whereby I may increase the capacity of the machine through a construction which will permit of a higher speed of relative movement between the can to be sealed and the seaming rollers, bringing the seaming rollers more rapidly from non-effective to effective positions and withdrawing the same more rapidly from effective positions after the seaming operation—this, in connection with positively timed relative movements of parts and a wholly automatic seaming operation. I might add that the present invention also contemplates a machine in which operation of the feeding mechanism may be quickly checked, as it should be when a container to be sealed is improperly positioned or the head thereof has become dislodged to the point of not only preventing the production of the desired seam but possibly to the extent of clogging the machine and breaking a part or parts thereof, without the necessity of stopping the heavier moving parts of the machine and thus having to overcome the inertia of these parts both in stopping and starting with consequent loss of time.

My invention will be more readily understood by reference to the accompanying drawings, forming a part of this specification, in which,

Figure 1 is a perspective view of a can heading machine embodying my invention;

Fig. 2 is a side elevation of the same, on a slightly enlarged scale, partly broken away, and the seaming mechanism being shown in substantially central section;

Fig. 3 is a side elevation, on an enlarged scale, of the can feeding mechanism;

Fig. 4 is an end view of the lower portion of the same, certain parts being omitted for the sake of clearness;

Fig. 5 is a sectional top plan view of this can feeding or advancing mechanism;

Fig. 6 is a fragmentary sectional view

taken substantially on the line 6—6 of Fig. 2;

Fig. 7 is a view similar to Fig. 5 with certain parts omitted and others included as 5 hereinafter more fully set forth;

Fig. 8 is detail sectional view of the clutch mechanism shown in Fig. 6, as hereinafter more fully described, and

Fig. 9 is an enlarged section taken substantially 10 on the line 9—9 of Fig. 2.

Referring now to the drawings in detail, numeral 11 designates the supporting frame of the machine which is preferably provided with a heavy base to give the same rigidity 15 and stability. In the lower portion of this frame is journaled the shaft 12 upon which is mounted the driving pulley 13 designed to have the usual belt connection with any suitable source of power. In the upper portion 20 of the frame 11 is journaled the shaft 14 upon which are mounted the pulleys 15 and 16 whereby said shaft 14 may be driven at variable speeds from the pulleys 17 on the shaft 12 by means of the belt 18.

25 In forwardly projecting arms 19 and 20 of the frame 11 is mounted the hollow rod 21, carrying at its lower end the chuck 22 which, in the common and well-known manner, is designed to enter the central depression 30 in a can top and support the overlapping flanges of the top and body portion of the can for the seaming operation.

Journaled in these forwardly projecting arms 19 and 20 is the shaft 23, rotated from 35 the shaft 14 by means of the intermeshed bevel gears 24 and 25. Surrounding the rod 21 is a sleeve 26 to which is secured a gear 27 in mesh with a gear 28' on the shaft 23, whereby said sleeve 26 is rotated on said rod, 40 said sleeve being supported by said gear 27 which rests upon the shoulder formed by the thrust-bearing 36. The sleeve 26 carries at its lower extremity a cylindrical eccentric head 28, journaled upon which is a collar 29 provided at its lower end with a flange or disk portion 30, the peripheral edge of which is up-turned and said up-turned portion interiorly screw-threaded for the reception of the annular washer 31.

50 A collar 34 has a bearing on the sleeve 26 and surrounds the collar 29. This collar is supported for independent rotation upon the shoulder formed by the eccentric head 28, and is provided at its lower end with a flange 35, the edge of which enters the 55 groove formed between the washer 31 and the disk 30, thus rotatively supporting said collar 29 through the disk portion 30 thereof. Mounted on the upper face of the disk portion 30 of the collar 29 is a swivel-block 37 (Fig. 9) slidable in a radially disposed slot 38 in the flange 35, wherefore it will be seen that while the collar 34 is supported by the eccentric head 28, these members 60 rotate independently of each other, and while

the collar 29 with its disk portion 30 is connected with the collar 34 and its flange 35 through the swivel-block 37 in the slot 38, whereby the former is rotated by and with the latter, these members have a certain freedom of bodily movement laterally with respect to each other.

The gears 27 and 28 being of the same size, the sleeve 26 with its eccentric head 28 will be rotated at the same velocity as 70 the shaft 23. At the lower end of the shaft 23 is provided a gear 39 in mesh with a gear 40 on the collar 34. The gear 39 is of slightly greater diameter than the gear 40, whereby said collar 34 will be rotated at 75 slightly greater velocity than the shaft 23, and, therefore, at a slightly greater velocity than the sleeve 26 with its eccentric head 28. Therefore, as the sleeve 26 and the collar 34 are rotated, the former will travel at a 80 slightly less velocity than the latter, whereby the relative positions of the eccentric head 28 and the collar 34 will be constantly varied to change the position of the disk 30 relative to the rod 21 which carries the 85 chuck 22. This relative movement, controlled by the swivel-block 37 in the slot 38, is fully shown and described by me in my earlier Patent No. 1,167,346, aforesaid, and for the purposes of this description it will suffice to state that as the eccentric head 28 and the collar 29 are rotated at slightly different velocities, the seaming rollers 33, suitably mounted on one side of the tool-carrying ring 32, which is detachably secured to 90 the underside of the disk portion 30 and the collar 29, will be successively brought into and out of work-engaging positions with respect to the chuck 22. The configuration of the working edge of each of the rollers 33 and that of the chuck 22 are too well known to require detailed description here, and the same is true with respect to the effect of the coöperative operation of rollers and chuck.

Mounted on the shaft 14 is the worm 44, 110 in mesh with a gear 45 loose upon a bushing 46 on the shaft 47, this shaft having bearings in the branches of an arm 48 projecting upwardly from the main frame of the machine. The bushing 46 with the 115 thrust-collar 49 are fixed to the shaft 47 by means of the pin 50, one end of the shaft 47 being bored out to receive the end of the rod 51, and this hollow end of the shaft 47 being provided with longitudinal slots 52 (Fig. 8) through which passes a pin or key 53 carried by the rod 51. This pin or key 53 is also secured at its ends to the collar 54 of the disk 55 which is loose upon the shaft 47. It will be seen, therefore, that the 120 rod 51 may be reciprocated for a limited distance within the end of the shaft 47 and thereby reciprocate the disk 55, these members, however, necessarily rotating in unison. To the face of the disk 55 is secured 125 130

the semi-annular member 56, an opposite and corresponding semi-annular member 57 being secured to the contiguous face of the gear 45. The gear 45, loose upon the shaft 47, is continuously rotated, and it will be apparent that as the rod 51 is reciprocated longitudinally within the bore at the end of the shaft 47, reciprocating therewith the disk 55 and its half-ring 56, the disk 55 will be forced in the direction of said gear 45, and at one point in each revolution of said gear the half-ring 56 will clear the half-ring 57 and be engaged by the latter to rotate the shaft 51 and therewith the shaft 47.

I have described above a preferred form of clutch mechanism for rotating the gear 58 on the shaft 47 from the constantly rotating shaft 14. This particular construction of clutch mechanism, however, is not essential to my invention, as it will be apparent that the shaft 47 may be driven by the shaft 14 through the interposition of any one of various forms of connections which are capable of disconnection when desired in many different ways. Nevertheless, attention is directed to the fact that any clutch mechanism employed should engage the shaft 47 and rotate the gear 58 at the same point in the rotation of the gear 45, for reasons which will be hereinafter made clear. This is preferably accomplished by me in the manner described, through the employment of the half rings 56 and 57, one mounted on the constantly rotating element and the other on the element to be rotated.

The gear 58 is in mesh with the gear 59 on the shaft 60 which has bearing in the arm 48 of the frame of the machine. This shaft 60 carries the beveled gear 61 in mesh with the gear 62 on the shaft 63. Mounted on the shaft 63 is the disk 64 having a cam-groove 65 (see dotted lines in Fig. 6) within which rides a roller at the end of the arm 66 of a bell-crank lever pivoted at 67 to the frame of the machine. A connecting rod 68 connects the end of the arm 66 with the arm 69 of a similar bell-crank lever pivoted at 70, the other arms 71 and 72 of said levers having pivotal connection with the lugs 73 and 74 of a frame which contains a horizontal run-way 76 for a roller 77. It will be apparent that upon rotation of the shaft 63, the cam-groove 65 in the disk 64 will operate to oscillate the arms 66 and 69, thereby alternately raising and lowering the frame 75, this frame being vertically reciprocated once for each revolution of the cam-disk 64 on the shaft 63.

Suitably mounted in the frame of the machine are the horizontal and parallel guide-
60 rods 78 and 79, slideable and rotatable upon which are the sleeves 84 and 85, respectively. Secured to these sleeves are the bars or levers 80 and 81, respectively, the meeting ends 65 of which are preferably off-set or half cut

away and these off-set portions interfitted, one of said bars (the bar 80, as shown) being provided with a pin 82 projecting into a longitudinal slot 83 in the other bar, thus insuring pivotal movement of said bars or 70 levers in unison to correspondingly rock the sleeves 84 and 85. The roller 77 is mounted at the end of the bar 81, and it will be apparent that as the frame 75 is raised and lowered, said sleeves will be rocked through 75 the medium of said bars.

Rigidly secured to these sleeves 84 and 85, respectively, are the opposite and corresponding frames 86 and 87, the frame 86 including the collars 87 and 88 on the sleeve 86 80 and the downwardly projecting arms 89 and 90. Similarly, the frame 87 includes the collars 91 and 92 on the sleeve 85 and the downwardly projecting arms 93 and 94. At the lower ends of the arms 89 and 90 is secured a casting 95, and at the lower ends of the arms 93 and 94 is mounted the casting 96. These castings 95 and 96 are of similar configuration, each being provided with preferably three recesses 97, these recesses 90 being circular in shape and arranged in pairs, whereby a circular can body may be engaged between opposite recesses of each pair.

It will be apparent that as the frame 75 95 is raised and lowered, thereby rocking the arms 80 and 81 in opposite directions, the sleeves 84 and 85 will be correspondingly rocked, operating through the frames 86 and 87 to reciprocate the members 95 and 96 100 horizontally, these members thus having the effect of jaws which close and open to engage and release can bodies interposed therebetween.

On the shaft 63 is also mounted the disk-wheel 98 to which is pivoted the connecting rod 99, at the other end of which are provided the rollers 100 adapted to travel in horizontal runways 101. This connecting rod is designed to reciprocate the carriage 105 which includes the frames 95 and 96, and in order to provide for a feature of adjustability, I interpose a substantially triangular-shaped member 102, having pivotal connection with the connecting rod 99 and to which 110 is pivoted the connecting rod 103, the other end of which is pivoted to the arm 104 of a bell-crank lever pivoted at 105'. The member 102 is provided with a vertical slot 105 through which projects a stud or pin (not 120 shown) on the rod 99, said stud or pin being threaded for the reception of the clamping nut 106, whereby the relative position of the member 102 may be rotatively varied to adjustably vary the relative position of the rods 99 and 103, whereby the starting and stopping positions of the plate or carriage 107 may be varied. The lever 104 is pivoted in lugs projecting upwardly from a plate 107, this plate being secured to and moving 130

with the sleeves 84 and 85. Projecting upwardly from this plate are the arms 108 and 109, carrying at their tops the cross bar 110, between which and the plate 107 is interposed the arm 111 which comprises the other arm of the bell-crank lever referred to. This arm 111, therefore, has a certain freedom of movement between the cross-bar 110 and the plate 107, whereby upon initial movement of the disk-wheel 98 and the connecting rod 99, upon rotation of the shaft 63, a certain interval of time will elapse prior to movement of said plate 107 under action of the connecting rod 103. This interval of time is to provide for the action of the disk-wheel 64 with its cam groove 65, which operates, just prior to movement of said carriage in one direction, to lower the frame 75 and close the can-engaging members 95 and 96 and engage the can bodies which have been properly positioned therebetween. Immediately following the engagement of these bodies, the disk wheel 98 will operate through the connecting rods and the lever 104, the arm 111 of which has now impinged against the plate 107, to carry said plate 107 in what may be termed a forward direction, carrying therewith the can bodies which have been engaged thereby and positioning the foremost of said bodies in the seaming mechanism.

Similarly, when the disk wheel 98 has turned through a half revolution, the arm 111 of the bell crank lever will be raised to contact with the plate 110 before the connecting rod 103 has the effect of operating to return the plate 107 to its initial position and therewith the members 95 and 96. During this interval of time, the disk wheel 64 with its cam-groove 65 will have operated to raise the frame 75 and thereby withdraw the members 95 and 96 from engagement with the can bodies to clear the same and permit of the return of said members to proper position for reengagement with the next succeeding can-bodies for repetition of the above-described operation.

The duration of these time intervals may be adjustably varied by means of the adjusting screw 111^a in the upper face of the arm 111, the extent of projection of which may be varied to slightly increase or decrease the length of the vertical stroke of said arm and thus correspondingly vary duration of each period of rest prior to reciprocation of the plate or carriage 107.

Suitably supported at one end upon the frame of the machine, and at the other end in any desired manner, I provide a runway 60 for the can bodies which comprise preferably two plates 112 and 113, separated to provide a space 114 therebetween for purposes which will be hereinafter set forth. I have shown secured to these plates side 65 guide strips 115 and 116, respectively, and

the provision of a top bar 117 so positioned as to retain the superposed tops of the can bodies in place in transit to the seaming mechanism. In mesh with the gear 62 on the shaft 63, driven by the gear 61 on the shaft 60, is the bevel gear 117' of the shaft 118, which carries the bevel gear 119 in mesh with a corresponding gear 120 on the vertical shaft 121. This shaft 121 is provided with the bevel gear in mesh with a corresponding gear 122 on a horizontal shaft 123 which is provided with a sprocket wheel 124 over which passes a chain 125, the upper leg of which runs in the space 114 between the plates 112 and 113. This chain 125 is provided with a series of lugs located at such distance from each other as to engage a series of can bodies and advance the same along the runway provided by the plates 112 and 113 and advance the forward can body to such position as to be engaged between the rearward recesses 97 in the members 95 and 96, substantially as shown and described in detail in my earlier Patent No. 1,167,345, aforesaid.

It has already been explained how the members 95 and 96 serve to grip this can body and advance the same one step, then release the same and return for the engagement of the next succeeding can body. At the same time the last-mentioned can body is being engaged, the one last engaged and advanced is again engaged by the middle recesses of the members 95 and 96, and so on, the foremost can body at each operation being positioned upon a preferably circular platform 126 on a vertical rod 127 and which is located directly underneath the chuck 22.

Projecting from the bearing collar 128 on the shaft 60, is an arm 129 to which is pivoted a bell-crank lever having one arm 130 provided with a roller operating in a cam groove 131 the face 132 of the gear 58 on the shaft 47. The other arm 133 of said bell-crank lever has pivotal connection at its end with one end of the rod 134 the other end of which is pivoted to the lever 135 fulcrumed at 136' in the frame of the machine. This lever 135 has connection through the links 136 with a vertically reciprocating carriage 137 which is adapted to raise and lower the rod 127 and therewith the platform 126, substantially as shown and described in another earlier Patent, No. 1,167,348, granted to me January 4, 1916, wherein, however, the platform was raised by hand instead of automatically as in the present invention.

The cam groove 131 is of such configuration that the rod 134 is lowered to raise the platform 126 just prior to effective co-operation between the seaming rollers 33 and the chuck 22. After this operation, the platform 26 is automatically lowered, and the seaming operation having been effected,

the can is forced into the chute 138 by the next succeeding can, which is positioned in the manner explained on said platform 126.

5 It is well known to those skilled in this art that the compression of the flanges from which the seam is formed against the chuck 22, frequently results in the frictional engagement of the can which prevents the same from being lowered by gravity with the platform 126. For the purpose of disengaging the can from the chuck after the seaming operation, I provide a plunger rod 141, reciprocable for a limited distance 10 within the hollow rod 21 and provided at its end with the pusher head 142. At the upper end of this rod is provided a cross bar 143 connected by links 144 to the ends of arms 145 on a short shaft 146. This 20 shaft is rocked by means of the lever arm 147, the free end of which is provided with a roller and which is raised and lowered by means of the cam 148 on the face of the gear 58. As the shaft 146 is rocked, 25 it will be apparent that the rod 141 will be raised and lowered, and this operation is so timed by the cam 148 that said rod is depressed simultaneously with depression of the platform 126. This construction and 30 operation is substantially the same as described by me in other earlier patents, more particularly Patent No. 1,167,346, aforesaid.

Under normal conditions of operation, the gear 45 is secured through the clutch described to the shaft 47, whereby rotation of said shaft 47 is continuous and the cans are automatically fed at proper intervals to the platform 126 in the manner described. In the event that a top or cover should be 40 come dislodged, or should a can body be improperly positioned, under which circumstances continued operation of the feeding mechanism would tend to clog the machine and possibly result in a breakage of some 45 part or parts thereof, I desire to provide for a stoppage of the feeding mechanism without stopping the operation of the other moving elements of the machine, as hereinbefore suggested. I therefore provide an 50 arm 151 pivoted to the shaft 63 which has suitable pivotal connection at its other end with the rod 51, this connection being shown between the two collars 152 and 153 on said rod. To this arm 151 is pivoted 55 the hand-lever 154, projecting to an accessible point in front of the machine, this lever operating through the arm 151 and the rod 51 to separate the disk 55 and its half ring 56 from the gear 45 and the half ring 57, 60 whereby the gear 45 will run loose upon the shaft 47 and operation of the feeding mechanism will be thereby stopped.

In order to insure operation of the can engaging devices prior to movements of the 65 reciprocating carriage, I may provide a

brake-bar 156 adapted to be frictionally engaged to a greater or less degree between the cross-bars 157 and 158, mounted upon the pins or posts 159 and 160 projecting downwardly from the plate 107. Compression springs 161 act against the bar 157 to provide this frictional engagement with the bar 156, and it will be apparent that by thus yieldingly retarding movement of the carriage, operation of the members or jaws 75 95 and 96 is insured prior to reciprocation of said carriage.

To further insure the retention of the loose can heads in proper positions on the can bodies during transit to the seaming mechanism, I provide pins 162 projecting upwardly from the members 95 and 96 and so positioned as to contact with the edges of the can cover when the can body is engaged by the members or jaws 95 and 96— 85 these covers, prior to the seaming operation, projecting beyond the side walls of the can bodies.

From the foregoing it will be seen that I have provided a machine in which the can- 90 engaging and feeding mechanism is simple in construction, dependable in operation and invariably operates at the proper time, and one in which actuation of said engaging and feeding means may be terminated at 95 any time irrespective of the relative positions of moving parts of the machine, and one in which, also, the actuating means for seaming mechanism such as shown and described has been simplified, and a machine 100 which is otherwise in its entirety simple in construction, dependable in operation and capable of operating at a high speed without great danger of breaking a part or parts thereof through improper positioning of the 105 work or dislodgment of one or both of the assembled parts to be joined together.

Many modifications of minor details of my improved can heading machine will doubtless readily suggest themselves to 110 those skilled in the art to which it appertains, and I therefore do not desire to limit my invention to the specific construction herein shown and described.

I claim as new and desire to secure by 115 Letters Patent:

1. In a machine of the character described, the combination, with a stationary support for the work, of an eccentric rotatable about the axis of said support, a tool-carrying 120 member rotatable on said eccentric, and a driving shaft, said eccentric and said member being each directly intergeared with said shaft whereby they are rotated at different and constant velocities.

2. In a machine of the character described, the combination, with means for suitably supporting the work and a stationary shaft carrying said supporting means, of a sleeve 130 rotatable on said shaft, an eccentric head

- carried by said sleeve, a tool-carrying member rotatable on said head, and a driving shaft, said sleeve and said member being directly intergeared with said driving shaft 5 whereby they are rotated at different and constant velocities.
3. In a can heading machine, the combination, with a chuck and a stationary shaft supporting said chuck, of an eccentric rotatable on said shaft, a member rotatable on said eccentric, a seaming roller carried by said member, and a driving shaft, said eccentric and said member being directly intergeared with said shaft whereby they are rotated at 10 different and constant velocities.
4. In a can heading machine, the combination, with a chuck and a stationary shaft supporting said chuck, of a sleeve rotatable on said shaft, said sleeve carrying an eccentric head, a member journaled for rotation on said head, said member carrying a seaming roller, and a driving shaft, said member and said sleeve being directly intergeared with said shaft whereby they are rotated at 15 different but slightly different velocities.
5. In a can heading machine, the combination, with a chuck and a stationary shaft supporting said chuck, of a sleeve rotatable on said shaft, said sleeve being provided with an eccentric head, a member journaled for rotation on said head, said member carrying a seaming roller adapted to coöperate with said chuck, a driving shaft and means for rotating the same 20 at a constant velocity, and gears on said driving shaft in mesh with a gear on said sleeve and a gear on said member, respectively, said gears being so proportioned as to rotate said sleeve and said member at 25 slightly different velocities.
6. In a can heading machine, the combination, with a chuck and a stationary shaft supporting said chuck, of a sleeve rotatable on said shaft, said sleeve being provided 30 with an eccentric head, a collar rotatable on said head, a member carried by said collar rotatable therewith but having a limited substantial radial movement independent thereof, said member carrying a seaming 35 roller adapted to coöperate with said chuck, a driving shaft and means for rotating the same at a constant velocity, and gears on said driving shaft in mesh with a gear on said sleeve and a gear on said collar, respectively, said gears being so proportioned 40 as to rotate said sleeve and said collar at different velocities.
7. In a can heading machine, the combination, with means for suitably supporting the assembled parts of the can to be headed, of a rotating bearing block eccentrically disposed with reference to said supporting means, a member mounted to rotate on said bearing block, a seaming roller carried by 45 said member, a driving shaft, and direct

connecting means between said shaft and said block and said member, respectively, to rotate said block and said member at uniformly different velocities.

8. In a can heading machine, the combination, with means for suitably supporting the assembled parts of the can to be headed, of a rotating bearing block eccentrically disposed with reference to said supporting means, a member mounted to rotate on said bearing block, a plurality of seaming rollers carried by said member, a driving shaft, and direct connecting means between said shaft and said block and said member, respectively, to rotate said block and said member 70 at uniformly different velocities.

9. In a can heading machine, the combination, with means for suitably supporting the assembled parts of the can to be headed, of a rotating bearing block eccentrically disposed with reference to said supporting means, a member mounted to rotate on said block, a seaming roller having fixed bearings in said member and being revolved thereby around said can parts, a driving shaft, and direct connecting means between said shaft and said block and said member, respectively, to rotate said block and said member 85 at uniformly different velocities.

10. In a can heading machine, the combination, with means for suitably supporting the assembled parts of the can to be headed, of a rotating bearing block eccentrically disposed with reference to said supporting means, a member mounted to rotate on said bearing block, a plurality of seaming rollers each having fixed bearings in said member and being revolved thereby around said can parts, a driving shaft, and direct connecting means between said shaft and said block 90 and said member, respectively, to rotate said block and said member at uniformly different velocities.

11. In a can heading machine, the combination, with means for suitably supporting the assembled parts of the can to be headed, of a rotating bearing block eccentrically disposed with reference to said supporting means, a sleeve rotatable on said bearing block, a member carried by said sleeve rotating therewith and having a limited substantially radial movement relative thereto, a seaming roller having fixed bearings in said member and being revolved thereby around said can parts, a driving 110 shaft, and direct connecting means between said shaft and said block and said sleeve, respectively, to rotate said block and said sleeve at uniformly different velocities.

12. In a can heading machine, the combination, with means for suitably supporting the assembled parts of the can to be headed, of a rotating bearing block eccentrically disposed with reference to said supporting means, a sleeve rotatable on said bearing 115

block, a member carried by said sleeve rotating therewith and having a limited radial movement relative thereto, a plurality of seaming rollers having fixed bearings in said member and being revolved thereby around said can parts, a driving shaft, and direct connecting means between said shaft and said block and said sleeve, respectively, to rotate said block and said sleeve at uniformly different velocities.

13. In a can heading machine, the combination, with the seaming mechanism, of means for successively delivering the assembled can parts thereto, said means comprising a suitable guide-way for said can parts, guide-rods paralleling said guide-way, sleeves slidable and rotatable on said rods, a carriage mounted on said sleeves and adapted to reciprocate the latter independent of rotation thereof, said sleeves carrying arms and said arms being provided at their free ends with can-engaging devices, means for reciprocating said carriage, said means including a lost-motion connection which provides a period of rest at the end of each stroke of reciprocation, and means for rocking said sleeves during each of said periods of rest.

14. In a can heading machine, the combination, with the seaming mechanism, of means for successively delivering the assembled can parts thereto, said means comprising a suitable guide-way for said can parts, guide-rods paralleling said guide-way, sleeves slidable and rotatable on said guide-rods, a carriage mounted on said sleeves and adapted to reciprocate the latter independent of rotation thereof, pairs of oppositely-acting oscillating arms projecting from collars fixed upon said sleeves and carrying at their free ends can-engaging devices, means for reciprocating said carriage, said means providing a period of rest at the end of each stroke of reciprocation, means for varying the duration of said period of rest, and means for rocking said sleeves during each of said periods.

15. In a can heading machine, the combination, with the seaming mechanism, of means for successively delivering the assembled can parts thereto, said means comprising a suitable guide-way for said can parts, guide-rods paralleling said guide-way, sleeves slidable and rotatable on said rods, a carriage mounted on said sleeves and adapted to reciprocate the latter independent of rotation thereof, pairs of oppositely-acting oscillating arms projecting from collars fixed upon said sleeves and carrying at their free ends can-engaging devices, means for reciprocating said carriage, said means providing a period of rest at the end of each stroke of reciprocation, means for varying the duration of said period of rest, and means for rocking said sleeves during each of said periods.

of said periods, said last-mentioned means comprising co-acting lever-arms fixed upon said sleeves and means for oscillating said lever-arms.

16. In a can heading machine, the combination, with the seaming mechanism, of means for successively delivering the assembled can parts thereto, said means comprising a suitable guide-way for said can parts, guide-rods paralleling said guide-way, sleeves slidable and rotatable on said rods, a carriage mounted on said sleeves and adapted to reciprocate the latter independent of rotation thereof, collars fixed upon said sleeves and carrying pairs of oppositely-acting oscillating arms provided at their free ends with can-engaging devices, means for reciprocating said carriage, said means providing a period of rest at the end of each stroke of reciprocation, means for adjustably varying the starting and stopping positions of said carriage, means for varying the duration of said periods of rest, and means for rocking said sleeves during each of said periods.

17. In a can heading machine, the combination, with the seaming mechanism, of means for successively delivering the assembled can parts thereto, said means comprising a suitable guide-way for said can parts, guide-rods paralleling said guide-way, sleeves slidable and rotatable on said rods, a carriage mounted on said sleeves and adapted to reciprocate the latter independent of rotation thereof, pairs of oppositely-acting oscillating arms projecting from collars fixed upon said sleeves and carrying at their free ends can-engaging devices, means for reciprocating said carriage, said means providing a period of rest at the end of each stroke of reciprocation, means for adjustably varying the starting and stopping positions of the carriage, means for varying the duration of said periods of rest, and means for rocking said sleeves during each of said periods, said means comprising co-acting lever-arms fixed upon said sleeves and means for oscillating said lever-arms.

18. In a can heading machine, the combination, with the seaming mechanism, of means for successively delivering assembled can parts thereto, said means comprising a reciprocable carriage having can-engaging devices mounted thereon, the latter being operable through the medium of oscillating arms on both sides of the path of travel of said can bodies, an arm on each side being provided with an operating lever and said levers being interconnected to move said arms simultaneously in opposite directions, a frame which includes a guide-way within which the end of one of said levers travels, and means for reciprocating said carriage horizontally and said frame vertically.

19. In a can heading machine, the combi-

nation, with the seaming mechanism, of means for successively delivering assembled can parts thereto, said means comprising a reciprocable carriage having can-engaging devices mounted thereon, the latter being operable through the medium of oscillating arms on both sides of the path of travel of said can bodies, an arm on each side being provided with an operating lever and said levers being interconnected to insure simultaneous movement of said arms in opposite directions, a frame which includes a guideway within which the end of one of said levers travels, and means on the same rotatable element for reciprocating said carriage horizontally and same frame vertically.

20. In a can heading machine, the combination, with the seaming mechanism, of means for successively delivering assembled can parts thereto, said means comprising a reciprocable carriage having can-engaging devices mounted thereon, the latter being operable through the medium of oscillating arms on both sides of the path of travel of said can bodies, an arm on each side being provided with an operating lever and said levers being interconnected to insure simultaneous movement of said arms in opposite directions, a frame which includes a guideway within which the end of one of said levers travels, a driving shaft for said delivering means, connecting means between said shaft and said carriage to reciprocate said carriage, and connecting means between said

shaft and said frame to raise and lower said frame.

21. In a can heading machine, the combination, with the seaming mechanism, of means for successively delivering assembled can parts thereto, said means comprising a reciprocable carriage having can-engaging devices mounted thereon, the latter being operable through the medium of oscillating arms on both sides of the path of travel of said can bodies, an arm on each side being provided with an operating lever and said levers being interconnected to insure simultaneous movement of said arms in opposite directions, a frame which includes a guideway within which the end of one of said levers travels, a driving shaft for said delivering means, means interposed between said shaft and said carriage to reciprocate said carriage, and means interposed between said shaft and said frame to raise and lower said frame, said carriage reciprocating means including a lost-motion connection to provide a period of rest at the end of each stroke of reciprocation, and said frame actuating connections operating during each period of rest.

In testimony of the foregoing, I have hereunto set my hand in the presence of two witnesses.

JULIUS BRENZINGER.
